UNITED STATES PATENT OFFICE.

PAUL E. DENIVELLE, OF SAN FRANCISCO, CALIFORNIA.

MANUFACTURE OF ARTIFICIAL-STONE STRUCTURES.

1,233,265.

Specification of Letters Patent. Patented July 10, 1917.

Original application filed October 20, 1915, Serial No. 56,879. Patent No. 1,212,331, dated January 16, 1917.
Divided and this application filed January 11, 1917. Serial No. 141,846.

To all whom it may concern:

Be it known that I, PAUL E. DENIVELLE, a citizen of the United States, residing at the city and county of San Francisco and 5 State of California, have invented a new and useful Improvement in Manufacture of Artificial-Stone Structures, of which the following is a specification.

This invention comprehends a process to 10 be used in the manufacture of artificial stone simulating travertin stone or marble, and adapted to be used especially for its architectural effects, and pertains especially to the method of surfacing and finishing structures already in place, such as walls, cornices, etc.

The method embraces the application of 15 colored plastic material or ingredients, such as Portland cement, plaster of Paris, Keene's cement, magnesite and water or other liquid substance with or without aggregates to an upturned negative form, or mold of existing type, of wood, plaster, cement, etc., wherein these colored materials are so applied before 20 the final set or crystallization of the mass, in a variety of progressive steps consecutively, as to produce in the cast or positive taken from said mold, form, etc., automatically as 25 a result of the progressive steps and special 30 application, a certain striated form of texture porousness in simulation of a stone known as "travertin" or "Roman travertin". This process has to do mainly with producing or obtaining a surface especially desirable for reproducing in architectural and 35 decorative effect; this method of use and effect being an innovation.

The method involves the use of the above 40 colored materials in a certain definite and novel manner during their direct application to a wall or ceiling, or similar surface, and before the set or crystallization is complete, in order that the resulting surface 45 may have a colored striated or porous surface in simulation of travertin or Roman travertin texture or stone of similar striated porosity; this form of use and effect being an innovation.

The drawings illustrate the application of 50 the invention simply in a schematic manner.

The figure is a horizontal cross-section illustrating the process.

The present application is a division of

my original application which has matured into Patent #1,212,331, dated January 16, 55 1917.

In proceeding by the present process I employ the following steps in the case of walls, ceilings, cornices, etc.

The plastic materials or ingredients, such 60 as Portland cement, Keene's cement, magnesite, plaster of Paris, or a combination of the ingredients, are applied to walls or ceilings, interior or exterior, whereby the resulting surface is made striated and porous of 65 the nature and for the purpose of producing a simulation or imitation of the surface that obtains in Roman travertin stone commonly known as "travertin"; the object being to incorporate several or all of the following 70 steps in accordance with the degree or perfection in imitation or simulation required in the finished surface from the architects' viewpoint.

1. To a concrete, brick, metal or wood lath, 75 or any similar form of construction B, one or two coats of plastic material or mortar, as 10, composed of plaster of Paris, Portland cement or Keene's cement and sand or aggregate, is applied and straightened to a fair 80 surface. This application may be varied in method and result; the object being to form a foundation for the steps which follow.

2. Next, a colored mixture, as 11, composed of white Portland cement, Keene's cement, magnesite, plaster of Paris, or similar materials, with or without a percentage of aggregate or sand added, is reduced to a consistency of a soft paste in semi-liquid form, by the addition of water or other 90 agency, and applied to the wall in that state by means of a trowel, float or similar device to a varying thickness, in accordance with the depth of porosity required in the finished result. This application is immediately straightened roughly by means of a rule or straight-edge. The foregoing coat is for the purpose of producing a background coating of the general color form required, of sufficient thickness to permit of 95 the next operation.

3. One or several mixtures of different colors of the foregoing ingredients, reduced with water or other liquid to a soft pasty consistency, is applied in a series of horizontal veins 12, of varying length, with a

narrow, long, soft brush, or other device immersed in the one or several colored mixtures successively and applied to the coating 11 by stippling in while the material of coat 11 is very soft. A light horizontal trowel action is repeatedly applied. This is for the purpose of providing light horizontally striated veins or lines of different colors or tones of color in the finished result.

10 4. While the foregoing coats 11 and 12 are still very soft, a sharp stipple is produced to the full depth of coatings 11 and 12 by means of a slender or narrow brush of stiff bristles held horizontally and applied in 15 a series of alternating sharp jabs and pressure, said stippled jabs being placed staggered, with varying sequence between the colored veins 12 described heretofore.

5. A light horizontal trowel application 20 follows. This is for the purpose of producing the greater porosity in texture markings required in the finished result; the form and nature of the bristles producing a jagged series of depressions, horizontally striated formation, and the trowel's pressure reducing the width of these depressions, together with providing an undercut quality to the stippling it would not otherwise have.

6. While the coating 11 is still soft, but in 30 an advanced stage approaching set or crystallization, a smaller series of jabs is applied in a horizontal rotation by means of a stiff wire brush enough to penetrate the surface, gradually hardening, and applied between 35 the grosser markings and veins described in operations two and three. This is for the purpose of producing the refinements of texture or horizontal strata of porous quality not provided or possible by prior operations 40 described.

7. The surface mixture 11, with its added veining mixture 12, is now finished by the application of vigorous troweling. This is for the purpose of removing all imperfections or 45 unevenness that may accrue during operations two, three, four, five, six and seven, and to leave a straight smooth surface of different color tones produced by the variegated striated veins and the shadows of the 50 depressions, such as are characteristic of Roman travertin, or stone commonly known as "travertin."

8. In such moldings, cornices, panel moldings, or forms of ornamentation as may require it, the same methods are applied in 55 forming the same as described in operations two, three, four, five, six and seven, except that following the last step a knife mold that has the form or outline of the object required will be used in addition to the foregoing methods of two, three, four, five, six and seven and run over the surface of the

object its full length to retain perfection of contour.

Having thus described my invention, what 65 I claim and desire to secure by Letters Patent is—

1. A process for the manufacture of striated artificial stone structures, which consists in preparing the surface of the article 70 to be treated and laying a soft background thereon, veining the same with a plastic material, stippling the veining, and troweling the same.

2. A process for the manufacture of striated artificial stone structures, which consists in preparing the surface of the article 75 to be treated and laying a soft background thereon, veining the same with a plastic material, stippling the veining, troweling the 80 same, and during crystallization of the deposit of material subjecting the same to further stippling.

3. A process for the manufacture of striated artificial stone structures, which consists in preparing the surface of the article 85 to be treated and laying a soft background thereon, veining the same with a plastic material, stippling the veining, troweling the 90 same, and during crystallization of the deposit of material subjecting the same to further stippling and finally to a vigorous troweling.

4. A process for the manufacture of striated artificial stone structures, which consists in depositing upon a soft background a 95 veining of plastic material, troweling the same, subjecting the troweled surface to stippling, and again troweling the same.

5. A process for the manufacture of striated artificial stone structures, which consists in depositing upon a soft background a 100 veining of plastic material, troweling the same, subjecting the troweled surface to stippling, and again troweling the same, and 105 then during crystallization subjecting it to more stippling.

6. A process for the manufacture of striated artificial stone structures, which consists in depositing upon a soft background a 110 veining of plastic material, troweling the same, subjecting the troweled surface to stippling, and again troweling the same, and then during crystallization subjecting it to more stippling, and finally to a vigorous 115 troweling.

In testimony whereof I have hereunto set my hand in the presence of two subscribing witnesses.

PAUL E. DENIVELLE.
